CLIP-ON SIDE SHIELD FOR AN EYE GLASS FRAME

George R. Hoffmaster, Reading, Pa., assignor to The Electric Storage Battery Company, Philadelphia, Pa.

Filed Feb. 4, 1964, Ser. No. 78,520

Term of patent 14 years

(Cl. D57—1)

Fig. 4.

Fig. 2.

Fig. 3.

Fig. 1.

FIG. 1 is a top perspective view of a clip-on side shield for an eyeglass frame, with the side shield shown in non-operating position, showing my new design;

FIG. 2 is a fragmentary side view thereof, with the side shield in operating position;

FIG. 3 is a front view of the clip-on attachment portion thereof; and,

FIG. 4 is a front view of the clip-on attachment portion thereof, taken on a reduced scale, the broken line showings of the clip-on attachment and eyeglass frame being for illustrative purposes only.

I claim:

The ornamental design for clip-on side shield for an eye glass frame, substantially as shown and described.
